Patented Nov. 29, 1921.

INVENTOR

Anthony F. Saltalamachia

ATTORNEY

UNITED STATES PATENT OFFICE.

ANTHONY F. SALTALAMACHIA, OF HUNTINGTON PARK, CALIFORNIA.

TABLE.

1,398,496.

Specification of Letters Patent. Patented Nov. 29, 1921.

Application filed September 10, 1919. Serial No. 322,936.

To all whom it may concern:

Be it known that I, ANTHONY F. SALTALAMACHIA, a citizen of the United States, residing at Huntington Park, in the county 5 of Los Angeles and State of California, have invented new and useful Improvements in Tables, of which the following is a specification.

My invention relates to tables, and it is 10 particularly adapted to be used in connection with and to be supported by the robe rack, which is usually found attached to the back of the front seat of automobiles.

The object of my invention is to provide 15 a table which will be simple, light and durable in construction, and which will be both extensible and foldable, which may be conveniently set up in an automobile to be used by its occupants for any desired purpose, 20 and which may be readily folded up and stored away in a minimum space, when not in use.

A further object of my invention is to 25 provide a table which will be light and may be folded in a minimum space for transportation, and may be conveniently set up against a fence or tree to be used in the serving of lunches or for other purposes.

Other objects will be disclosed in the following description, will be pointed out in 30 the claims, and embodied in the accompanying drawings, in which:

Figure 1 represents a side elevation of my 35 invention as it would appear when in use, supported by the robe rail or rack secured to the back of the front seat of an automobile, parts being broken away and shown in section, to more clearly bring out the details of construction.

Fig. 2 is a plan view of the same.

Fig. 3 is a transverse section through my 40 table, showing it in a folded position.

Fig. 4 is an enlarged section taken on the line 4-4 of Fig. 1.

Fig. 5 is an enlarged section taken on the line 5-5 of Fig. 2.

In carrying out my invention I employ a 45 pair of standards 10 and 11, preferably formed of strap metal, each standard having a disk 12, formed at its upper end provided with a centrally disposed bore 13 and a plurality of radially disposed serrations 14, designed to act as clutch teeth. To standards 10 and 11 are hinged respectively the arms 15 and 16 also preferably formed of strap metal, which are each twisted at right

angles as at 17, and have formed on one of each of their respective ends the disks 18, which are provided with the centrally disposed threaded apertures 19, and the radially disposed serrations or clutch teeth 20 adapted to engage with serrations 14 on standards 10 and 11 to hold arms 15 and 16 in adjusted angular relation with said standards.

In order to hold members 10 and 15 and 50 11 and 16 in adjusted relation and to form a hinge between the same, I provide the bolts 22 provided with the winged heads 23, which pass through apertures 13 in the standards 10 and 11 respectively, and are threaded into the respective apertures 19 in arms 15 and 16.

Each of the arms 15 and 16 are provided 55 with slots 25 and stretched across the space formed between said arms, and resting thereon, is a suitable board 26, which serves as the table. Passing through apertures in opposite ends of board 26 are the carriage bolts 27, which pass through the slots 25, and have threaded on their free ends the butterfly nuts 28. By this arrangement it will be seen that the board or table 26 may be clamped firmly to the arms 15 and 16 by means of the butterfly nuts 28, and when 60 desirable the board may be adjusted rearwardly on said arms by simply loosening the nuts 28, and sliding said board to the desired position and then tightening up on the nuts again.

By the foregoing construction it is obvious 65 that the board or table 26 may be adjusted to a level position and clamped in such position by means of the wing bolts 23, and the clutch members 14 and 20. It is also 70 obvious that by loosening the wing bolts 23, the table 26 may be moved into parallel relation with standards 10 and 11, resting in between the same, as clearly shown in Fig. 3 of the drawings. When the device 75 is in this position it will readily be seen that it may be packed or stored away in a minimum amount of space, or it may be placed back into the robe rack, where it will rest 80 snugly against the back of the front seat.

Although I have described my table as being 85 particularly adapted to be used in connection with the robe rack of an automobile, it is obvious that other means may be employed of securing standards 10 and 11 to 90 the back of the front seat, or that standards 10 and 11 may be secured to a fence or tree 95 100 105 110

in any suitable manner, whereby the table may be used for any desired purpose.

What I claim is:

1. In combination with the back of a motor vehicle seat having a robe rail adjacent the top edge thereof, of a pair of standards each provided with an arm hinged to its upwardly extending end, said standards being maintained in position by the vehicle robe rail, a table supported on said arms, and means for locking said arms at various angles to said standards.

2. A portable table construction, comprising

ing in combination with a vehicle seat back provided with a robe rail, of a pair of standards detachably supported in position by said robe rail and seat back, a pair of arms secured to the upper ends of said standards, means to adjust said arms at various angles, and a table top adjustably mounted on said arms.

In witness that I claim the foregoing I have hereunto subscribed my name this 27th day of August, 1919.

ANTHONY F. SALTALAMACHIA.
